(57) **CLAIM**

The ornamental design for an “orthopedic plate,” as shown and described.

DESCRIPTION

FIG. 1 is a right top perspective view of a first embodiment of an orthopedic plate comprising a left plate wherein the right plate is a mirror image of the left plate, showing my new design;

FIG. 2 is a first side view thereof;

FIG. 3 is a second side view thereof;

FIG. 4 is a first end view thereof;

FIG. 5 is a second end view thereof;

FIG. 6 is a top view thereof;

FIG. 7 is a bottom view thereof;

FIG. 8 is a right top perspective view of a second embodiment of an orthopedic plate comprising a right plate wherein the left plate is a mirror image of the right plate, showing my new design;

FIG. 9 is a first side view thereof;

FIG. 10 is a second side view thereof;

FIG. 11 is a first end view thereof;

FIG. 12 is a second end view thereof;

FIG. 13 is a top view thereof;

FIG. 14 is a bottom view thereof;

FIG. 15 is a right top perspective view of a third embodiment of an orthopedic plate comprising a right plate wherein the left plate is a mirror image of the right plate, showing my new design;

FIG. 16 is a first side view thereof;

FIG. 17 is a second side view thereof;

FIG. 18 is a first end view thereof;

FIG. 19 is a second end view thereof;

FIG. 20 is a top view thereof; and,

FIG. 21 is a bottom view thereof.

1 Claim, 7 Drawing Sheets
